UNITED STATES PATENT OFFICE

147,932

DESIGN FOR A MASSAGING DEVICE OR SIMILAR ARTICLE

Leland H. Snyder, Chicago, Ill., assignor, by mesne assignments, to Quality Appliances, Inc., Chicago, Ill., a corporation of Illinois

Application February 15, 1946, Serial No. 126,592

Term of patent 3½ years

(Cl. D83—1)

To all whom it may concern:

Be it known that I, Leland H. Snyder, a citizen of the United States and a resident of the city of Chicago, in the county of Cook and State of Illinois, have invented a new, original, and ornamental Design for a Massaging Device or Similar Article, of which the following is a specification, reference being had to the accompanying drawing, forming a part thereof.

On the drawing:

Figure 1 is a side view of the massaging device or similar article, showing my new design.

Figure 2 is an end elevational view, and

Figure 3 is a top plan view thereof.

I claim:

The ornamental design for a massaging device or similar article, as shown.

LELAND H. SNYDER.
